(57) **CLAIM**

The ornamental design for a control interface for a vehicle steering wheel, substantially as shown and described.

DESCRIPTION

FIG. 1 is a perspective view of a control interface for a vehicle steering wheel;

FIG. 2 is a front view of the control interface;

FIG. 3 is a left side view of the control interface;

FIG. 4 is a right side view of the control interface;

FIG. 5 is a top view of the control interface; and,

FIG. 6 is a bottom view of the control interface.

In the drawings, the broken lines depict environmental subject matter only and form no part of the claimed design.

1 Claim, 4 Drawing Sheets
